UNITED STATES PATENT OFFICE

FRANK G. CARRINGTON, OF ANNISTON, ALABAMA, ASSIGNOR TO FERRIC ENGINEERING COMPANY, OF ANNISTON, ALABAMA, A CORPORATION OF DELAWARE

APPARATUS FOR COOLING MOLDS

Application filed May 10, 1927. Serial No. 190,362.

This invention relates to a cooling system and more particularly to a cooling system for use in a rotary casting apparatus.

Heat exchange between a mold in a rotary casting operation and molten metal results in an increase in the temperature of the mold and a cooling of the metal. The artificial cooling of the mold and the heat of the molten metal deposited within the mold therefore 5 counteract each other, so far as the temperature of the mold is concerned. In the prior cooling systems, the cooling of the entire mold is commenced at the same moment. But, as the metal is poured in the mold in 10 a column which progresses along the length of the mold, that portion of the mold where the last particle of metal is poured has been cooled for a longer time prior to the deposition of metal there than any other portion of 15 the mold prior to its receipt of metal. The metal deposited at the termination of the pouring, therefore, is subjected to more rapid and intense cooling than any other portion of the mold.

20 As the texture of a casting varies with the rapidity of cooling to which it has been subjected, there is a consequent variance of texture along the length of the casting. Usually, the portion of the casting poured last 25 cooled so suddenly that it has become case-chilled. A case-chilled object is of little commercial use, for it is unworkable. In order to render such an object available for use in ordinary operations, it is necessary to 30 subject it to an annealing process.

The problem of cooling the mold, therefore, is on the one hand, to adequately cool the mold so that it may be used over a series of casting operations, and on the other hand 35 to provide a cooling system which cools the poured metal so gradually that the additional and expensive step of annealing heretofore necessitated, will be quite largely, if not altogether, obviated.

40 Reference is made particularly to my co-pending application Serial No. 172,355, filed March 3, 1927, wherein I have set forth one form of cooling apparatus which overcomes the difficulties above enumerated. The invention which is the subject matter of this

application embodies certain modifications of my co-pending application.

An object of this invention is a method of cooling a mold.

Another object of this invention is to devise a method of cooling a mold gradually and progressively.

Yet another object of this invention is an apparatus for sectionally cooling a mold.

A further object of this invention is a cooling system for progressively cooling a mold.

A still further object of this invention is to provide a compact, yet effective, cooling system for a rotary mold.

And yet another object is to devise a cooling system wherein the cooling of the mold is synchronized with the pouring of the metal.

To accomplish the above and other important objects as will more fully hereinafter appear, my invention consists in a cooling member, means in the member for varying the operative length thereof, and other means for regulating the first mentioned means.

There is set forth in the accompanying drawings one form of apparatus which will accomplish the desired results. It is to be understood that these drawings do not constitute any limitation on my invention, for various modifications thereof may be made without in any way exceeding the scope and spirit of this invention.

In the accompanying drawings, Figure 1 is a top view of a casting mold and cooling system therefor, partly in elevation and partly in section;

Fig. 2 is a cross sectional view of Fig. 1, along the line 2—2, looking in the direction of the arrows;

Fig. 3 is a more detailed view of the plunger shown in Fig. 1;

Fig. 4 is a side elevational view of the mold and a partially sectional and partially elevational view of the cooling apparatus;

Fig. 5 is a more detailed view in perspective of the plunger and its actuating means;

Fig. 6 is a diagrammatic showing of means for synchronizing pouring of the metal and cooling of the mold;

Fig. 7 is a view along the line 7—7 of Fig. 6, looking in the direction of the arrows.

Referring more particularly to Fig. 1, a rotary casting mold 1 is rotatably mounted upon trunnions 2. The trunnions revolve upon roller boxes 3 which are suitably fixed to the base of the cooling apparatus. A split bearing member 4 is provided as an additional support for the mold. The mold is rotated by means of the gears 5 upon its periphery which mesh with actuating gears 6 mounted upon a driving shaft 7. The shaft 7 is rotated by any suitable operating means, not shown. For the purpose of more clearly understanding the operation of the cooling system, I have numbered the bell end of the mold 5' and the opposite end 6. The enlarged portion 5' of the mold may be dispensed with when desired, its principal purpose serving to aid in the formation of a bell on a pipe.

A trough 7', shown in Figs. 6 and 7, extends 20 within the mold and usually commences to pour at the bell end 5', while the mold is rotating. While it is pouring, the trough is gradually withdrawn from the end 5' toward the end 6, this movement, together with 25 the rotation of the mold, serving to deposit the metal spirally. It may be desired at certain places in the process to retain the trough stationary for a time, thus insuring a larger deposit of molten metal. This is particularly likely to be desired at the bell end of the 30 pipe.

Mounted above the mold shown in the drawings and supported by a standard 8 and the bearing member 4 is a fluid dispersing member 9. This member is usually of pipe construction, although any other suitable chamber may be used. Apertures 10 in the bottom of the chamber 9 allow the discharge of a fluid from the pipe. While I have shown the member 9 supported above the mold and provided with apertures in its bottom, the fluid dispersing member may be located opposite any point on the circumference of the mold and have its apertures suitably located to 45 spray upon the mold the cooling medium. Under certain circumstances, it may be advisable to employ a plurality of fluid dispersing members.

Within the fluid dispersing member 9 is a 50 plunger 11, which has a fluid tight fit with the walls of the member 9, but at the same time is capable of sliding therein. Attached to the plunger are cables 12 and 13. A single cable may be employed, of course, passing 55 through the plunger, provided the cable and plunger are stationary with respect to each other. The purpose of this cable is to slide the plunger 11 within the channel of the member 9. In place of the cable, a chain or 60 other pliable actuating means may be employed. The cable 12 passes around a sheave 14 rotatably supported on a shaft 15, thence around one circumference 16 of a rotatable sheave 17. The cable also passes around a 65 sheave 18 mounted upon a shaft similar to

15, and again through another guide 19 on the sheave 17. From thence it goes to a point of termination 21 where it is fixedly held by suitable means, not shown. The cable 13 passes through a series of sheaves similar to 70 those for the cable 12—first through 22, thence the periphery 23 of the sheave 24, thence around the sheave 25 and back to the smaller groove 26 of 24 and finally to its termination 29 where it is likewise fixedly held by means, 75 not shown.

The sheaves 17 and 24 are rotatably mounted upon a shaft 31 having collars 32 into which fit fingers 33 of a rack.

The series of sheaves 14, 17 and 18, it will 80 be noted, are within a box 34. This box is connected to the fluid dispersing member 9 by means of a channel 35. Upon one end 36 of the box there is located a fluid tight gland 37. This permits the movement of the shaft 31 within the box but prevents any leakage from the box. The box 34 is water tight, as is also the member 9 except for the apertures 11. A cooling medium is supplied into the box 34 and flows into the member 9. Inasmuch as the plunger 11 is water tight, however, no water can pass to the right, in the drawings, of the plunger. Movement of the plunger will vary the operative length of the member 9.

As the rod 31 is moved to the left, for instance, the cable 13 is withdrawn from the member 9. At the same time the movement of the shaft 31 permits of the extension of the cable 12 in the pipe 9. This reciprocation therefore changes the position of the plunger 11 in the pipe, altering the length of the pipe which is dispersing a cooling medium.

It is not necessary that the sheaves 14, 17 and 18 be positioned within the box 34 in contact with a fluid, but this arrangement is desirable for it is difficult to secure an effective gland for a cable. The gland 37, however, permits reciprocation of the rod 31 105 without any leakage from the box.

In Fig. 2 there is shown a pipe 38 which feeds the box and cooling system with a cooling medium. A pressure regulating valve, not shown, is mounted on this pipe in 110 order to maintain the fluid in the pipe 9 at a constant pressure. A shaft 39 is shown which rotates a gear 41. This gear coacts with the rack above referred to. There is shown in this figure the arrangement of the sheave 17 with the larger guide member 16 and the guide member 19 of smaller circumference. These two guideways are 115 concentric and integral. The yoke 42 on the rod 31 is shown for supporting the sheave 17. The cable 12 is shown resting in the two guideways.

In Fig. 3 there is shown the particular method of attaching the cables 12 and 13 to the plunger 11, comprising staples 43 to 130

which the ends of the cables are attached. Other suitable fastening means may be used, or as above suggested, there may be one continuous cable holding the plunger 11 stationary with respect thereto. A cooling medium 44 is being discharged from the apertures 10. This discharge is to the left of the plunger, while that portion of 9 to its right is free from the cooling medium.

10 In Fig. 4 there is shown in more detail the arrangement of the cables and the sheaves. There is also shown a rack 45, heretofore referred to, and upon which are attached the fingers 33 fitting within the collars 32 of the 15 shaft 31. The underneath surface of this rack is provided with teeth which coat with the gear 41. The rack 45 is provided with flanges 46, as shown in Fig. 5, which fit in grooves in the base of the box 34 and serve 20 as guides for the rack. Any other suitable means may be employed which permit the axial movement of the rack but prevent any lateral or vertical movement. The guide-way may be at some other place in the apparatus, if desired.

As the gear 41 is revolved, its teeth mesh with the teeth of the rack 45 and move the latter axially. The fingers 33 fitting into the collar of the shaft and attached to the 30 rack, transfer this movement to the shaft. As above pointed out, movement of the shaft results in a change in position of the plunger.

In Fig. 5 there is included in one view the complete actuating apparatus. The yokes 32 for holding the sheaves 17 and 24 are shown mounted on the shaft 31. The fingers 33 of the rack are of sufficient length to permit a slight sliding movement of the shaft in a vertical plane.

40 The actuating means for the shaft 39 may be a motor, a cylinder or any other mechanical device. Its action should be timed, however, in relationship to the movement of a pouring trough. The result to be obtained, 45 so far as timing is concerned, is movement of the plunger at the same rate and in the same direction as movement of the pouring trough. The relationship between the plunger and the pouring trough, which is preferable, is 50 one wherein the plunger is maintained directly above the spout of the pouring trough. In this way the cooling of the exterior of the mold will be concomitant and coincidental with the molten metal deposited within the 55 mold.

However, certain variations may be made in this connection wherein either the plunger 11 precedes or succeeds the spout of the trough in its movement along the length 60 of the mold, depending upon whether, with respect to the pouring, premature or subsequent cooling of the mold is desired. The determination of this will depend upon the particular circumstances of a casting operation.

There is shown diagrammatically in Fig. 6 an arrangement whereby the cooling of the mold and pouring of the metal may be synchronized. A carriage 47, mounted upon wheels 48, supports the trough 7. Also mounted upon the carriage is a ladle 49 designed to supply the trough with molten metal. The carriage runs upon a track 51 and moves the trough 7 axially with respect to the mold. An arm 52 suitably mounted on the carriage 47 is attached to a chain 53. This chain is carried by a sprocket 54 suitably geared to a motor 55. Another sprocket 56 is rotated by the chain and revolves an axle 57, as shown in Fig. 7, upon which is fixed another sprocket 58. This latter sprocket carries a chain 59 which is mounted upon a sprocket 61. This last sprocket rotates the shaft 39, which actuates, by means of the gear 41, the rack 45.

The gearing employed in this apparatus should be such that the plunger 11 will move in the pipe 9 at the same rate of speed as the trough 7 moves in the mold. As above pointed out, the spaced relationship of the plunger and spout of the trough may be varied as occasion demands. The plunger 11 may move in the pipe 9 directly above the end of the trough 7, or its movement may precede or follow the spout, as desired.

It is, of course, obvious that other means may be employed to accomplish this synchronization of the pouring and cooling. While I have shown and described a casting apparatus wherein the mold remains stationary and the pouring trough moves with respect thereto, it is to be understood that this invention may be employed in an apparatus in which the mold moves axially and the trough remains stationary. Slight adjustments only would be required to care for this modification. While I have not shown in detail an apparatus for accomplishing the desired results under such an arrangement, it is to be understood that the adaptation of my invention to an apparatus of this character will not exceed the scope of the appended claims.

The proper adjustment of the operating means will preclude a sudden chilling of the metal poured into the mold, and thus prevent the case-hardening of the casting. Certain variations may be made in this particular without exceeding the progressive cooling herein set forth. By removing to a great extent, if not altogether, the necessity of annealing the casted object, this invention is of great importance to the casting industry.

Its compactness is likewise an advantage not to be overlooked. The cooling system herein set forth does not exceed the length 125 of the mold. My co-pending application, while providing for a similar cooling effect, has actuating means for the plunger which extend beyond the mold. In the present invention considerable space is saved by rea-

son of the fact that the actuating mechanism is positioned on the side of the mold and does not extend beyond the mold.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. A cooling system comprising a cooling member, means for varying the operative length of said member and means actuating said first mentioned means comprising a pulley arrangement.

2. A sectional cooling system comprising a plunger mounted in a cooling member, and flexible means for actuating the plunger.

3. In a sectional cooling system for a rotatable mold comprising a member for dispersing a cooling medium, a plunger slidably mounted therein, a cable for moving said plunger, a series of fixed rotatable sheaves, and other sheaves movable for actuating said cable.

4. A sectional cooling system for a rotary casting mold comprising a plunger in a fluid dispersing member, a cable attached to the plunger, and means for actuating the cable at a predetermined rate.

5. In a sectional cooling system for a rotary casting mold, a plunger in a fluid dispersing member, a cable attached to the plunger for sliding the same in the member, and means operatively connected with a metal depositing device for actuating the cable at a predetermined relationship to the deposition of molten metal within the mold.

6. A cooling system for a rotary casting mold comprising a fluid dispersing member, means for varying the operative length of the member, flexible actuating means therefor, a series of stationary rotatable sheaves for guiding said actuating means, and other sheaves stationary with respect to each other but relatively movable to the first mentioned sheaves for regulating the actuating means.

7. A cooling system for a rotatable mold comprising a fluid dispersing member, another member cooperating therewith for varying the operative length of the fluid dispersing member, a cable attached to the last mentioned member, and connecting means therefor comprising a rod rotatably supporting sheaves.

8. In a rotary mold cooling system having a cooling member and a plunger slidably mounted therein, actuating means for the plunger comprising a sheave supporting member including a yoke mounted on a shaft,

plunger actuating sheaves carried thereby and means for moving the member.

9. In a cooling system for a rotatable mold, actuating means for a plunger in a fluid dispersing member comprising sheaves supported by an axially movable rod and means for moving the rod so that the plunger slides at a predetermined rate.

10. In combination with a casting mold, a plunger slidable in a fluid dispersing member, a sheave supporting rod coacting with the plunger, and means operatively connected with a metal depositing device for axially moving the rod so that the plunger slides in the fluid dispersing member at a desired rate and predetermined relationship to the deposition of molten metal within the mold.

11. A centrifugal casting apparatus comprising a rotary mold, a ladle for depositing metal therein, means for moving the ladle, a fluid dispersing member mounted in juxtaposition to said mold adapted to disperse a cooling medium thereon, a plunger slidably mounted in said dispersing member, flexible means connected with said plunger for sliding the same, sheaves for actuating the flexible means, and means associated with means for moving the ladle for imparting motion to the sheaves.

12. In a cooling system, an apertured cooling medium dispersing conduit, a plunger slidably mounted therein, a casing in communication with one end of the conduit, fixed and movable sheaves positioned in said casing, flexible means connected with the plunger adapted to pass over the sheaves, and means extending into the casing for moving the movable sheaves.

13. In a cooling system, an apertured cooling medium dispersing conduit, a plunger slidably mounted therein, a casing in communication with one end of the conduit, fixed and movable sheaves positioned in said casing, flexible means connected with the plunger adapted to pass over the sheaves, fixed and movable sheaves positioned adjacent the other end of the conduit, a second flexible means passing thereover, means connecting the movable sheaves, and means for operating the connecting means for sliding the plunger in the dispersing conduit.

In testimony whereof I affix my signature.
FRANK G. CARRINGTON.
